(57) **CLAIM**

The ornamental design for a digital video camera, as shown and described.

DESCRIPTION

FIG. 1 is a top, front and left side perspective view of a digital video camera showing our new design;

FIG. 2 is a bottom, rear and left side perspective view thereof with the display portion in an open position;

FIG. 3 is a front elevational view thereof;

FIG. 4 rear elevational view thereof;

FIG. 5 is a top plan view thereof;

FIG. 6 is a bottom plan view thereof;

FIG. 7 is a right side elevational thereof; and,

FIG. 8 is a left side elevational thereof;

The broken lines shown in the drawings illustrate environmental structure and form no part of the claimed design.
